UNITED STATES PATENT OFFICE

LEE C. SHARP, OF OMAHA, NEBRASKA, ASSIGNOR TO AMERICAN CAN COMPANY, OF NEW YORK, N. Y., A CORPORATION OF NEW JERSEY.

CAN HEADING AND CRIMPING MACHINE.

No. 807,049.

Specification of Letters Patent.

Patented Dec. 12, 1905.

Application filed March 9, 1903. Serial No. 146,826.

To all whom it may concern:

Be it known that I, LEE C. SHARP, a citizen of the United States, residing in Omaha, in the county of Douglas and State of Nebraska, have invented a new and useful Improvement in Can Heading and Crimping Machines, of which the following is a specification.

My invention relates to improvements in can heading and crimping machines.

The object of my invention is to provide a can heading and crimping machine of a simple, efficient, and durable construction which will operate to automatically assemble can-bodies and can-heads in position on each other and crimp the heads thereon rapidly and cheaply.

My invention consists, in connection with a feed-chute having three passages or compartments, one for the can-bodies and two for the can-heads parallel and adjacent to each other, of a feed wheel or carrier having a series of pockets for receiving, conveying, holding, and registering each a can-body and a pair of heads therefor in alinement with each other, a pair of reciprocating and revolving plungers or chucks for pushing the can heads and body together and revolving the can during the crimping operation, a movable can-body former or shaper operating in conjunction with the pocket on the feed wheel or carrier to shape or round the can-body to regular form before the heads are pushed thereon by the rotating and reciprocating heads or chucks, and a pair of movable crimping-rollers to crimp the flanges of the can-heads snugly to the can-body as the can heads and body are rotated.

It further consists, in connection with the carrier-wheel having the series of pockets for receiving and centering the can-bodies and can-heads, of a pair of reciprocating and rotating chucks or plungers for pushing the can-heads upon the can-body and rotating the cans arranged above the center of the feed wheel or carrier, so that when each pocket is brought to and being brought to the position for registration with the chucks or plungers by the rotation of the feed wheel or carrier the pocket will not be turned over sufficiently to cause the can-body and can-heads to roll or fall out of the same. In other words, the combination of the chucks or plungers and crimping-rollers with the feed wheel or carrier and the can head and body holding pockets thereon is such that when the feed wheel or carrier turns to bring each

pocket into position for operation of the chucks or plungers and the crimping-rollers the pocket will be sufficiently upright to properly retain the can-heads and can-body therein.

My invention further consists in providing a spring or yielding connection between the rotating and reciprocating plungers or chucks and the mechanism for reciprocating the same, so that the can bodies and heads will be yieldingly grasped and forced together and provide compensation for variation in the length of the cans.

It further consists in actuating the crimping-rollers by a spring or springs to force or press the same against the cans during the crimping operation.

It further consists in the particular combination of the carrier or feed wheel and the can head and body receiving and centering pockets therein, with the reciprocating and rotating plungers or chucks, wherein the chucks or plungers are slightly eccentric to the can lying in the pocket in the carrier, so that when the plungers are forced together to push the countersunk can-heads upon the can-body they will operate to slightly lift or move the can-heads, and through them the can-body, out of contact with the periphery of the pocket, thus leaving the can heads and body to rotate freely, and thereby preventing the pocket from having any braking or friction action against the rotating can-body and can-heads. This materially reduces the power to operate the machine and also insures certainty and perfection of the crimping operation, as the cans are left entirely free to rotate under the action of the chucks.

My invention further consists in the novel construction of parts and devices and in the novel combinations of parts and devices herein shown or described.

In the accompanying drawings, which form a part of this specification, and in which similar letters of reference indicate like parts throughout all the figures, Figure 1 is a front elevation of a can heading and crimping machine embodying my invention. Fig. 2 is a plan view, partly broken away. Fig. 3 is a vertical section on the line 3 3 of Fig. 2. Fig. 4 is a detail section on line 4 4 of Fig. 2. Fig. 5 is a detail section on line 5 5 of Fig. 2. Fig. 6 is a detail section on line 6 6 of Fig. 1, and Fig. 7 is a detail end view of the pawl-and-ratchet mechanism for intermittently rotating the feed wheel or carrier. Fig. 8 is a

central vertical section on line 8 8 of Fig. 1. Fig. 9 is a central vertical section of the feed-chute. Fig. 10 is a cross-section on line 10 10 of Fig. 8. Fig. 11 is a cross-section on line 11 11 of Fig. 8. Fig. 12 is a detail front elevation of the feed wheel or carrier. Fig. 13 is a detail longitudinal section of two of the pockets of the feed wheel or carrier, taken radially through the carrier. Fig. 14 is a detail section taken on the line 14 14 of Fig. 9. Figs. 15 and 16 are detail sectional views showing the parts in different positions and illustrating the relative eccentric arrangement of the rotating and reciprocating plungers or chucks in respect to the can in the pocket of the feed wheel or carrier. Fig. 17 is a cross-section of one of the pockets on line 17 17 of Fig. 15. Fig. 18 is a detail view of one of the crimping-rollers. Fig. 19 is a detail vertical section through one of the thrust-blocks, and Fig. 20 is a detail view showing a modification.

In the drawings, A represents the frame of the machine.

B is an intermittently-rotating feed wheel or carrier having a shaft B' journaled on the frame of the machine and provided with a series of can head and body receiving and centering pockets b, each somewhat exceeding in length the combined length of the can-body and the two can-heads and each when the machine is used for operation upon round cans semicircular in shape. Each of these can head and body receiving and centering pockets b is provided with a pair of semi-annular or semiperipheral raised ribs b', upon which the can-body X rests, and forming recesses or enlargements b² at each end of the pocket to receive the flanges x of the can-heads X' and an intermediate recess or enlargement b³ to give room for the projecting tongue x' of the tearing-strip of a key-opening can. The can-heads X' each have a countersink x², and the flanges x of the can-heads are flaring, so that the heads slip easily onto the body when brought into registry or approximate registry with each other.

C is the feed-chute for the can-bodies and can-heads, the same being tripartite or having three passages or compartments, a middle one c for the can-bodies and two side ones c' c² for the can-heads, the two latter being separated from the former by thin blades or partitions c³ c⁴ of brass or sheet metal. The can heads and bodies roll down the tripartite chute C together in close endwise juxtaposition to each other, being separated only by the thin blades or partitions c³ c⁴, and drop or pass simultaneously into the pocket b of the carrier B, the can-body itself serving to hold the can-heads in their upright or edgewise position and preventing them from tilting inward or toward each other.

D D are a pair of reciprocating and rotating plungers or chucks by which the can-

heads are pushed upon the can-body and the cans rotated during the crimping operation, the same being secured to rotating and reciprocating shafts D' D', journaled in suitable bearings D² on the frame of the machine.

D³ D³ are a pair of stationary stripping cups or hoods secured to or made integral with the frame A and furnished with sockets or cavities d and loosely fitting and surrounding the plunger heads or chucks D and which when the chucks or heads D are withdrawn serve to prevent the can-heads sticking thereto.

C² C² are a pair of side guides which extend from the chute C to the cups or hoods D³ D³, the same forming a continuation of the side guides C' of the chute C. These side guides are flush with the inner faces of the cups or hoods D³ and serve to hold or guide the can-heads in position as they are conveyed by the carrier B into registry with the plungers or chucks D.

The plungers or chucks D are mounted on the frame slightly eccentric to the can or to the position of the can when resting in the pocket b of the carrier, so that when the plungers or chucks are moved toward each other to push the can-heads on the can-body the plungers or chucks entering the countersinks of the can-heads will serve to slightly lift the can-heads, and through them the can-body, from the pocket b and out of contact with the periphery or wall thereof, as will be readily understood from Figs. 15 and 16 of the drawings. This result or slight eccentricity in the position of the plungers or chucks D D in respect to the can-heads and can-body in the pocket b is preferably secured by boring or making the pocket b slightly larger (in diameter if the can heads and bodies are round) than the can-heads and can-body which rest therein. I prefer to make in practice the pockets about one-sixteenth of an inch larger in diameter in its corresponding parts than the can-heads and can-bodies fitting therein, thus leaving a clearance between the pocket and can heads and body of about one thirty-second of an inch when the can heads and body are forced together and clamped or chucked between the rotating plungers or chucks D D. As the can heads and body are rotated by the chucks D D they will thus be entirely clear and free from and out of contact with the surface of the pocket b. The feed wheel or carrier B, having the series of pockets b, is preferably made in two separate and independently-adjustable sections B, B, secured to the shaft B' by set-screws B², so that the two sections of the feed wheel or carrier may be set closer together or farther apart, according to the length of the cans being operated upon. The stripping cups or hoods D³ are also preferably laterally adjustable to and from each other and made in separate pieces from the frame A and secured thereto by screws D⁴.

5 F is a movable shaping device or former which coacts with the pockets b in the feed wheel or carrier B to round up or true the can-body to its regular form prior to the movement of the chucks or plungers D D to push the can-heads upon the can-body.

10 G G are a pair of movable crimping-rollers, which operate to bend or crimp the flanges x of the can-heads X' close and snug against the can-body while the can heads and body are being held and rotated by the rotating plungers or chucks D D.

15 The can-body former F and the crimping-rollers G G are preferably mounted upon or carried by one and the same movable holder F', which is secured to or made integral with the overhanging operating-lever F², which is pivoted by a pin F³ to the frame of the machine. The shaper or former F is adjustably 20 and yieldingly connected to the movable holder F' by means of a stem f, sleeve f', spring f², and set-screw f³, the stem f having a slot f⁴, through which a pin f⁵ on the sleeve f' extends to prevent the stem f' turning in the 25 sleeve. A rod f⁶, having stop-nuts f⁷, limits the movement of the stem f in respect to the sleeve f'. The shaper or former F, or its stem f, is provided with an arm f⁸, having an adjusting-screw f⁹, which strikes against a 30 fixed stop f¹⁰ on the frame of the machine and limits the movement of the shaper or former F toward the can-body. The position of the sleeve f' on the holder F' is fixed and adjusted by the set-screw f³.

35 The crimping-rollers G are each adjustably and independently connected to the movable holder F', by which they are operated, through the connecting-stem g and set-screws g' and g², there being one stem g and one pair of set-screws g' g² for each crimping-roller, so that the crimping-rollers can be independently adjusted on the movable holder or head F', through which they are operated. As the former or shaper F has a spring connection 40 with the movable holder or head F', the holder F' can continue its movement toward the can as required to bring the crimping-rollers into operation after the shaper or former F is arrested by the stop-arm f⁸ engaging the fixed 45 stop f¹⁰. This enables the shaper or former F and crimping-rollers G G to be both carried on and operated by one and the same movable head or holder F', while at the same time causing the shaper or former F to engage and round up the can-body before the chucks or plungers D D push the can-heads on the can-body and clamp the same thereto and before the crimping-rollers are brought 50 into action against the rotating can. In this 55 way I materially simplify the construction and operation of the machine.

The movable holder F' is or may be preferably operated, as before stated, through a lever F², which is actuated by a cam h on the 60 driving-shaft H, which engages a lever h',

pivoted to the frame at h² and connected by a link h³ with the lever F². A spring H⁴ retracts the lever h'. A spring or yielding connection h⁴ h⁵ h⁶ is interposed between the crimping-rollers G G and the cam h or other 70 means that may be employed for operating the crimping-rollers. This spring connection h⁴ h⁵ h⁶ is preferably located in the connecting-links h³, this being most conveniently done by providing the link h³ with a sleeve h⁴, 75 spring h⁵, and a separate section h⁶, which slightly telescopes in the sleeve h⁴, a pin h⁷, and slot h⁸, limiting the sliding or telescoping movements of the parts h⁴ h⁶ in respect to each other. The spring h⁵ is normally compressed under 80 the tension required to produce the requisite pressure of the crimping-roller upon the flange of the can-head under normal conditions. If, however, through irregularities in the cans or can-heads the pressure of the crimping-roller against the flange of the can-head becomes too 85 great and liable to produce injury to the can or machine, the yielding or spring connection between the crimping-roller and its operating-cam permits the crimping-roller to give or 90 yield, thus insuring the performance of perfect work under all conditions with ease and without danger. The cans are thus crimped with a uniform pressure, and all danger of the crimping-roller cutting, cracking, or breaking 95 the tin in cases where the can happens to be a little large through extra thickness, extra amounts of solder upon the side seam, or other causes is entirely avoided.

100 As will be observed from the drawings, Fig. 8, the rotating and reciprocating plungers or chucks D D, former F, and crimping-rollers G G are so combined with the feed wheel or carrier B and can head and body receiving and centering pockets b therein that 105 the chucking and crimping operation takes place well above the center or axis of the stationary carrier B, so that the pocket b containing the can heads and body is sufficiently upright to prevent the can heads and body 110 from falling or rolling out of the pocket when the pocket is brought and while it is being brought into position for registration or co-operative action with the plungers or chucks D D and former and crimping-rollers, and 115 the three-part chute C for the can-heads and can-bodies is also combined with the feed wheel or carrier B, as shown in Fig. 8, so that one pocket b of the carrier is in a substantially 120 upright position or substantially over the center or axis of the carrier at the mouth or discharge end of the chute C, so that the can heads and bodies may roll and drop by gravity downward into one pocket, while the can heads and body in the next preceding pocket 125 are in registry and co-operative position with the rotating plungers or chucks D D, former F, and crimping-rollers G G. By this means each pair of the can-heads and each can-body are only moved one step of the carrier B from 130

the position wherein they are received to the position wherein the heads are applied to the can-body and crimped thereon. This facilitates the speed and certainty of operation of the machine, as the can-heads and can-body have no opportunity to become displaced in respect to each other before the heading and crimping operation is performed. This particular combination of the three-part feed-chute with the feed wheel or carrier and the rotating chucks or plungers and crimping-rollers wherein the can heads and bodies are received and headed and crimped in adjacent pockets of the carrier also enables me to employ in my invention a feed wheel or carrier of small or minimum diameter, which also materially increases the practical speed of the machine, as the centrifugal motion and force of the carrier on the can-heads and can-bodies, tending to throw the same out of the pockets or displace them, is thus reduced to a minimum and made much less than in machines heretofore in use, while at the same time the momentum or loss of power required in stopping and starting the intermittently-rotating carrier is also very greatly reduced.

K is the discharge-chute. Its bottom is provided with a yielding or hinged section K', held in position by a spring k and provided 30 with a stripping-finger k' to strip the cans from the pockets b or prevent their sticking therein. This hinged or yielding bottom of the discharge-chute permits the same to open and discharge the cans rearwardly in cases where, as sometimes happens through the carelessness of attendants, the discharged cans are permitted to pile or wall up in the discharge-chute against the feed-wheel, and thus cause stoppage of the machine and destruction of 35 cans. This yielding section of the discharge-chute acts as a safety gate or device.

M is a supplemental stripping-finger secured to the bottom of the feed-chute C, which insures the ejection of any cans that may be 45 stuck in the pocket of the wheel, as sometimes may happen where a very large can occurs. The feed wheel or carrier B has an intermediate recess, channel, or open space, preferably between the two sections B B thereof, 50 to accommodate the stripping-fingers k' and M.

N N are seats for the operators or attendants who place the heads in the can-head-feed passages or compartments c' c'' of the chute C. The chute C, it will be observed, is an inclined 55 one, and the passages or compartments for receiving the can heads and bodies are open at the top.

P is a hinged plate or guard which fits over the feed-chute at the mouth thereof and prevents the can-bodies or can-heads from being crowded out of their proper channels at the end or mouth of the chute.

The intermittently-rotating feed wheel or carrier B is given a step-by-step movement, 65 as required, by means of a ratchet b' on its

shaft B', which is engaged by a pawl b' on a swinging-arm b', connected by a link b' with a crank or arm b' on the driving-shaft H. The feed-wheel B is held or locked in position for proper registration with the chute C and with 70 the heading and crimping mechanism by means of a friction-brake Q and friction-wheel Q' on the shaft B' of the feed-wheel, the friction-brake being furnished with a compensating spring q and an adjusting-screw q'.

The reciprocating and rotating plungers or chucks D D are constantly rotated by pulleys d' d' on their shafts D' D' through suitable driving-belts. The plungers or chucks D D are reciprocated as required by means of 80 cams H' on the driving-shaft H through the connecting-levers d', having racks or segment-gears d' on their upper ends, which engage toothed thrust-boxes d' d', fitting between collars d' d', d' d' on the shafts D' of the 85 plungers or chucks D D. The collars d' d' are made in the form of ball-bearing cups and in connection with the ball-bearing cup d' and balls d' give a ball-bearing connection between the reciprocating thrust-blocks d' d' and 90 the shafts D' D'. This enables the plungers or chucks D D to be rotated easily and at great speed and materially increases the practical speed and capacity of the heading and crimping machine. A yielding or spring connection 95 of any suitable form—as, for example, d' d' d' d'—is interposed between the rotating and reciprocating plungers or chucks D D and the driving-shaft H, by which each of the same are operated. This spring or yielding connection may be located at any point desired 100 between the plunger and its operating-shaft. In practice I prefer to locate this yielding or spring connection between the cam H' and the shaft H and to construct the same substantially as illustrated in Fig. 6—that is to say, 105 of a spring d', a cup or collar d', fixed to the shaft H, and a movable sleeve d', which bears against the spring, and a plate or washer d', which holds the flanged sleeve in place. The 110 spring is normally under compression and operates to yieldingly hold the cam H' on the shaft H. Another or equivalent construction for this spring connection is indicated by the dotted lines in Fig. 1, wherein the spring is 115 made integral with the lever d'. The construction illustrated in Fig. 6 is, however, preferred.

R R are tables or pans upon which the loose heads are placed preparatory to being put into the can-head passages c' c'' of the chute C by the operators sitting on the seats N.

As will be seen from Fig. 8, the crimping-roller G is located below the axis or center of the rotating can, and the movable holder F and lever F' move the crimping-roller toward the can in a direction approximately a tangential one to the periphery of the can owing to the location of the pivot of the lever F, and this causes the crimping-roller to contact with 130

the rotating can by a kind of wiping or dragging action thereagainst and prevents any tendency toward vibration or chattering of the crimping-roller against the rotating can, 5 as is the case where the crimping-roller is moved radially or toward the center of the can.

As will be seen from Fig. 18, the crimping-roller F is journaled in the forks f¹¹ of the stem f on a removable pin or pivot f¹², which 10 is furnished with a split key f¹³, extending through one of the forks f¹¹ to hold the pivot-pin in position and prevent it from turning, while at the same time permitting the crimping-roller to be quickly and easily removed 15 and replaced without the use of any tools for this purpose. This is a matter of convenience, as the crimping-rollers require frequent examination and repairing or dressing.

I claim—

20 1. In a can heading and crimping machine, the combination with a three-part chute having passages or compartments for can-bodies and can-heads, of an intermittently-rotating can-body feed wheel or carrier having a series 25 of pockets therein for receiving each a pair of can-heads and a can-body and centering the same with each other, a movable can-body shaper or former, a pair of reciprocating and rotating plungers or chucks for pushing the 30 can heads and body together and rotating the can, and a pair of movable crimping-rollers, substantially as specified.

2. In a can heading and crimping machine, the combination with a three-part feed-chute, 35 having passages or compartments in juxtaposition to each other for the can-bodies and can-heads, and an intermittently - rotating feed wheel or carrier having a series of pockets for receiving, conveying, holding and center- 40 ing with each other the can-bodies and can-heads, a pair of reciprocating and revolving plungers or chucks coöperating in turn with each of the pockets of said carrier for pushing the can-heads on the can-body and rotat- 45 ing the can, and a pair of movable crimping-rollers for crimping the can-heads on the can- body, substantially as specified.

3. In a can heading and crimping machine, the combination with a three-part chute, hav- 50 ing passages or compartments for can-bodies and can-heads, of an intermittently-rotating can-body feed wheel or carrier having a series of pockets therein for receiving each a pair of can-heads and a can-body and centering the 55 same with each other, a pair of reciprocating and rotating plungers or chucks coöperating in turn with each of the pockets of said carrier for pushing the can heads and body together and rotating the can, and a pair of 60 movable crimping - rollers, substantially as specified.

4. In a can heading and crimping machine, the combination with an intermittently-rotat- 65 ing feed wheel or carrier having a series of 70 pockets, each adapted to receive and center

with each other a pair of can-heads and a can- body, of a pair of rotating and reciprocating plungers or chucks coöperating in turn with each of the pockets of said carrier, and a pair of movable crimping-rollers, substantially as 75 specified.

5. In a can heading and crimping machine, the combination with an intermittently-rotating feed wheel or carrier having a series of 80 pockets, each adapted to receive and center with each other a pair of can-heads and a can-body, of side guides for holding the can-heads in an upright position, a pair of rotating and reciprocating plungers or chucks coöperating in turn with each of the pockets of said carrier, and a pair of movable crimping-rollers, sub- 85 substantially as specified.

6. In a can heading and crimping machine, the combination with an intermittently-rotating feed-wheel having a series of pockets, 85 each adapted to receive and center a can-body and a pair of can-heads, of a pair of reciprocating and rotating plungers or chucks coöperating in turn with each of the pockets of said carrier, the centers of which plungers or 90 chucks are slightly eccentric to or out of line with the can-heads and can-body resting in the pocket of the feed wheel or carrier, which is in position for registration or coöperation with said plungers or chucks, whereby the 95 plungers or chucks are caused to lift the can-heads and can-body out of contact with the pocket while the cans are being rotated, sub- 100 substantially as specified.

7. In a can heading and crimping machine, 100 the combination with an intermittently-rotating feed-wheel having a series of pockets, each adapted to receive and center a can-body and a pair of can-heads, of a pair of reciprocating and rotating plungers or chucks coöperating in turn with each of the pockets of said carrier, the centers of which plungers or 105 chucks are slightly eccentric to or out of line with the can-heads and can-body resting in the pocket of the feed wheel or carrier, which is in position for registration or coöperation with said plungers or chucks, whereby the 110 plungers or chucks are caused to lift the can-heads and can-body out of contact with the pocket while the cans are being rotated, and 115 a movable crimping-roller, substantially as specified.

8. In a can heading and crimping machine, the combination with an intermittently-moving 120 feed wheel or carrier having a series of pockets therein adapted each to receive and center with each other a pair of can-heads and a can-body, of a pair of reciprocating and rotating plungers or chucks coöperating in turn with each of the pockets of said carrier, the 125 pockets in said feed wheel or carrier being slightly larger in diameter than the can-bodies and can-heads resting therein, whereby the plungers or chucks are caused to lift the can-heads and can-body out of contact with the 130

pocket while the can is being rotated, substantially as specified.

9. In a can heading and crimping machine, the combination with an intermittently-moving feed wheel or carrier having a series of pockets therein adapted each to receive and center with each other a pair of can-heads and a can-body, of a pair of reciprocating and rotating plungers or chucks coöperating in turn with each of the pockets of said carrier, the pockets in said feed wheel or carrier being slightly larger in diameter than the can-bodies and can-heads resting therein, whereby the plungers or chucks are caused to lift the can-heads and can-body out of contact with the pocket while the can is being rotated, and a movable crimping-roller, substantially as specified.

10. In a can heading and crimping machine, the combination with a can head and body receiving and centering pocket, of a pair of rotating chucks or plungers, one movable toward the other, the pocket being larger in diameter than the can heads and body resting therein to cause the chucks or plungers to lift the can head and body out of contact with the pocket while the can is being rotated, substantially as specified.

11. In a can heading and crimping machine, the combination with a can head and body receiving and centering pocket, of a pair of rotating chucks or plungers, one movable toward the other, the pocket being larger in diameter than the can heads and body resting therein to cause the chucks or plungers to lift the can head and body out of contact with the pocket while the can is being rotated, and a movable crimping - roller, substantially as specified.

12. In a can heading and crimping machine, the combination with a can head and body receiving and centering pocket, of a pair of rotating plungers or chucks, one movable toward the other, the centers of said plungers or chucks being slightly eccentric or out of line with the can head and body resting in said pocket, whereby the chucks or plungers are caused to lift the can head and body out of contact with the pocket as the can is rotated, substantially as specified.

13. In a can heading and crimping machine, the combination with a can head and body receiving and centering pocket, of a pair of rotating plungers or chucks, one movable toward the other, the centers of said plungers or chucks being slightly eccentric or out of line with the can head and body resting in said pocket, whereby the chucks or plungers are caused to lift the can head and body out of contact with the pocket as the can is rotated, and a movable crimping-roller, substantially as specified.

14. In a can heading and crimping machine, the combination with a chute having passages for can-bodies and can-heads, of a feed-wheel

having receiving and centering pockets for can-bodies and can-heads, and a pair of plungers coöperating in turn with each of said can-body and can-head receiving pockets on said feed-wheel substantially as specified.

15. In a can heading and crimping machine, the combination with a chute having passages for can-bodies and can-heads, of a feed-wheel having receiving and centering pockets for can-bodies and can-heads, and a pair of rotating plungers or chucks coöperating in turn with each of said can-body and can-head receiving pockets on the feed-wheel, one having a reciprocating movement to and from the other, substantially as specified.

16. In a can heading and crimping machine, the combination with a chute having passages for can-bodies and can-heads of a feed-wheel having receiving and centering pockets for can-bodies and can-heads, a pair of rotating plungers or chucks, coöperating in turn with each of said can-body and can-head receiving pockets on the feed-wheel, one having a reciprocating movement to and from the other, and a movable crimping-roller, substantially as specified.

17. In a can heading and crimping machine, the combination with a chute having passages for can-bodies and can-heads, of a feed-wheel having receiving and centering pockets for can-bodies and can-heads, a pair of rotating plungers or chucks, one having a reciprocating movement to and from the other, and a spring or yielding connection through which thrust is imparted to one of said plungers or chucks, substantially as specified.

18. In a can heading and crimping machine, the combination with a chute having passages for can-bodies and can-heads, of a feed-wheel having receiving and centering pockets for can-bodies and can-heads, a pair of rotating plungers or chucks, one having a reciprocating movement to and from the other, a movable crimping-roller, and a spring or yielding connection through which pressure is applied to said crimping-roller to force it against the rotating can, substantially as specified.

19. In a can heading and crimping machine, a three-part feed - chute having passages or compartments for can-heads and can-bodies in juxtaposition to each other, a can-body and can-head feed-wheel having a series of pockets adapted to simultaneously receive can-heads and can-bodies from said feed-chute and convey them to a position to have the heads forced upon the body, and reciprocating plungers coöperating in turn with each of the pockets on said feed-wheel substantially as specified.

20. In a can heading and crimping machine, a feed-chute having passages for can-bodies and can-heads, of a feed wheel or carrier having can-body and can-head receiving and centering pockets, the mouth of the chute registering with a pocket on the feed wheel or carrier when the same is in an upright position,

and plungers coöperating in turn with each of the can head and body receiving pockets on the feed-wheel substantially as specified.

21. The combination with a pair of rotating and reciprocating plungers or chucks, of a movable crimping-roller, and means for moving the crimping-roller against the rotating can in a direction approaching a tangential one as contradistinguished from a radial one, to cause the crimping-roller to have a kind of wiping or dragging action on the rotating can and prevent vibration or chattering of the crimping-roller, substantially as specified.

22. In a can heading and crimping machine, the combination with a feed-wheel having can head and body receiving pockets, of a pair of reciprocating and rotating plungers or chucks, and antifriction thrust-blocks through which said chucks or plungers are reciprocated, substantially as specified.

23. The combination with a feed wheel or carrier having can head and body receiving and centering pockets, of a pair of rotating and reciprocating plungers, a movable former or shaper, a pair of movable crimping-rollers, and a movable holder upon which said former or shaper and said crimping-rollers are all mounted, substantially as specified.

24. The combination with a feed wheel or carrier having can head and body receiving and centering pockets, of a pair of rotating and reciprocating plungers, a movable former or shaper, a pair of movable crimping-rollers, and a movable holder upon which said former or shaper and said crimping-rollers are all mounted, said former or shaper having a spring or yielding connection with said holder, substantially as specified.

25. The combination with a feed wheel or carrier having can head and body receiving and centering pockets, of a pair of rotating and reciprocating plungers, a movable former or shaper, a pair of movable crimping-rollers, and a movable holder upon which said former or shaper and said crimping-rollers are all mounted, said former or shaper having a spring or yielding connection with said holder, and a fixed stop for arresting the movement of the former or shaper, the spring or yielding connection between said former and shaper and said holder permitting the holder and crimping-rollers carried thereby to continue their movement toward the can after the former or shaper is stopped, substantially as specified.

26. In a can heading and crimping machine, the combination with chucks or plungers for grasping and rotating the cans, of a can head and body centering pocket, a movable shaper or former, a crimping-roller, and a movable head or holder carrying the crimping-roller and shaper or former, substantially as specified.

27. The combination with a pair of rotating chucks or plungers, of a pair of independently-

adjustable crimping-rollers, a movable head or holder upon which both of said crimping-rollers are carried, and a can-body former or shaper also mounted upon said movable head or holder, substantially as specified.

28. The combination of the feed wheel or carrier provided with a series of pockets, of a discharge-chute having a yielding or hinged bottom, and a stripping-finger secured to said yielding bottom, substantially as specified.

29. In a can heading and crimping machine, the combination with a feed-chute having can head and body passages or compartments, of a feed-wheel having can head and body receiving pockets, a pair of rotating and reciprocating plungers, and a pair of stripping cups or hoods surrounding said plungers, substantially as specified.

30. In a can heading and crimping machine, the combination with a feed-chute having can head and body passages or compartments, of a feed-wheel having can head and body receiving pockets, a pair of rotating and reciprocating plungers, a pair of stripping cups or hoods surrounding said plungers, and side guides extending from said cups or hoods to the feed-chute, substantially as specified.

31. The combination with a pair of rotating and reciprocating plungers or chucks, of a pair of stripping cups or hoods, and a pair of crimping-rollers substantially as specified.

32. The combination with a pair of rotating and reciprocating plungers for pushing can-heads upon a can-body, of a stripping device loosely fitting the plunger to strip the can therefrom as it is withdrawn, and a pair of crimping-rollers substantially as specified.

33. The combination with a pair of rotating and reciprocating plungers for rotating the can, of an arm bearing against the can to stop its rotation after being released by the chucks or plungers, substantially as specified.

34. In a can heading and crimping machine, a three-part feed-chute having passages for can-heads and can-bodies in juxtaposition to each other, each of the can-head passages being open at the top and provided with an enlarged or beveled entrance to facilitate the placing of the can-heads therein, substantially as specified.

35. In a can heading and crimping machine, a three-part feed-chute having passages for can-heads and can-bodies in juxtaposition to each other, each of the can-head passages being open at the top and provided with an enlarged or beveled entrance to facilitate the placing of the can-heads therein, and the inner wall or partition of said can-head feed-passage being higher than the outer one, substantially as specified.

LEE C. SHARP.
